UNITED STATES PATENT OFFICE.

JACK I. POSES, OF NEW YORK, N. Y., ASSIGNOR TO A. A. VANTINE & CO., INC., OF NEW YORK, N. Y., A CORPORATION OF NEW YORK.

DESIGN FOR AN INCENSE BOX.

Application filed October 25, 1927. Serial No. 23,880. Term of patent 3½ years.

To all whom it may concern:

Be it known that I, JACK I. POSES, a citizen of the United States of America, residing at New York, county of Bronx, and State of New York, have invented a new, original, and ornamental Design for an Incense Box, of which the following is a specification, reference being had to the accompanying drawing, forming part thereof.

Fig. 1 is a front elevational view of a box showing my new design;

Fig. 2 is a side elevational view; and
Fig. 3 is a perspective view.

I claim as my invention:

The ornamental design for an incense box substantially as shown.
